UNITED STATES PATENT OFFICE.

JULIUS SCHMOHL AND ERNST LAUSCHKE, OF CHICAGO, ILLINOIS, ASSIGNORS TO THE MATHIER MANUFACTURING COMPANY, OF PHILADELPHIA, PENNSYLVANIA.

DESIGN FOR A FONT OF PRINTING-TYPE.

SPECIFICATION forming part of Design No. 19,722, dated March 25, 1890.

Application filed February 17, 1890. Serial No. 340,793. Term of patent 3½ years.

To all whom it may concern:

Be it known that we, JULIUS SCHMOHL and ERNST LAUSCHKE, citizens of the United States, both residing at Chicago, in the county of Cook and State of Illinois, have invented and produced a new and original Design for a Font of Type, of which the following is a specification, reference being had to the accompanying typographic impression, forming part thereof.

The accompanying impression shows a font of type setting forth the characteristic features of our design, which consists of, first, the slope-pendants with knobs, as A, M, N, X, and Y; second, scroll-work, as in capitals B, C, D, G, J, P, R, and S and $; third, peaked pendants, as in capitals K and R and lower case h, k, m, and n; fourth, peaked figures; fifth, logotype "and."

We claim—
A font of type, as shown and described.

JULIUS SCHMOHL.
ERNST LAUSCHKE.
